No. 36,590.

Patented October 13, 1903.

UNITED STATES PATENT OFFICE.

JOHN WILSON BROOKER, OF SAPP, GEORGIA.

DESIGN FOR A REIN-GUIDE.

SPECIFICATION forming part of Design No. 36,590, dated October 13, 1903.

Application filed September 8, 1903. Serial No. 172,408. Term of patent 14 years.

To all whom it may concern:

Be it known that I, JOHN WILSON BROOKER, a citizen of the United States, residing at Sapp, in the county of Whitfield and State of Georgia, have invented a new, original, and ornamental Design for a Rein-Guide, of which the following is a specification.

This invention relates to a new, original, and ornamental design for a rein - guide, as shown in the accompanying illustration, in which is represented a perspective view of my rein-guide, showing my new and original design.

I claim as my invention—

The ornamental design for a rein-guide as 15 shown.

In testimony that I claim the foregoing as my own I have hereto affixed my signature in the presence of two witnesses.

JOHN WILSON BROOKER.
